UNITED STATES PATENT OFFICE.

DAVID W. KENNEY, OF ST. MARYS, WEST VIRGINIA.

OSCILLATING STUFFING-BOX.

SPECIFICATION forming part of Letters Patent No. 670,900, dated March 26, 1901.

Application filed June 30, 1900. Serial No. 22,108. (No model.)

To all whom it may concern:

Be it known that I, DAVID W. KENNEY, a citizen of the United States, residing at St. Marys, in the county of Pleasants and State of West Virginia, have invented certain new and useful Improvements in Oscillating Stuffing-Boxes; and I hereby declare the following to be a full, clear, and exact description of the invention, such as will enable others skilled in the art to which it appertains to make and use the same.

My invention relates to that class of stuffing-boxes which are used for packing what is known as the "polished rod" of a pumping oil-well.

The object of my invention is to provide an oscillating stuffing-box which will entirely overcome the wear of said box and rod by reducing the friction to a minimum. I accomplish the above result as shown in the accompanying drawings, in which—

Figure 1 is a side elevation showing my invention, and Fig. 2 is a vertical sectional view of the same.

In the drawings, A represents a socket, which is formed in two sections a and b and rigidly secured together by bolts c. The lower section b is threaded at the bottom for the purpose of screwing it onto the top of the tubing d. Within the socket A is a hollow ball B, the upper end of which is provided with threads for screwing the stuffing-box D therein.

By the use of my invention the friction is entirely overcome, with the exception of the point where the polished rod C passes through the stuffing-box, whereas by the use of the old method of connecting the stuffing-box direct to the top of the tubing the friction and wear on the stuffing-box and polished rod, caused by the movement of the walking-beam, are so great as to cause the rod to cut or the box to

wear in a short time, so as to allow the oil to spray out over the derrick-floor.

It will be readily understood that the walking-beam in making its stroke causes the polished rod to pull against one side of the stuffing-box when it is traveling upward and likewise against the opposite side on the downward movement, as the stuffing-box is firmly secured to the top of the tubing, while by the use of my device the stuffing-box D and ball B are allowed to rock within the socket A with the side movement of the polished rod, thereby overcoming all wear in the box and on the rod. The oscillation of the ball B in the socket A is caused by the variation of the end of the arm of the walking-beam, to which the rod is attached from a right line, and this depends upon the distance between the point where the rod is attached to the pivotal point of the arm, and whatever distance it may be the rod must spring or yield just that much between the stuffing-box and the pump-piston.

Any desired lubricant may be applied at the top of the socket for keeping the parts oiled.

Any suitable packing e may be employed for forming a tight joint between the two sections of the socket.

Having described my invention, what I claim is—

An oscillating stuffing-box, consisting of a socket A, a hollow ball B, within the socket having an elongated portion which is threaded for the purpose of receiving the stuffing-box proper D, and the lower part of the socket being screw-threaded to the top of the tubing, all substantially as shown and for the purposes described.

DAVID W. KENNEY.
